UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,103, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The nature of my design is fully represented by the section of the pattern illustrated in the drawing, the main feature being the variegated stripe A, which is repeated throughout the pattern, B representing a portion of the plain body of the fabric, which intervenes between and separates the stripes. The stripe A is composed of a great number of minor parallel

bars, stripes, or ribs, of varying widths, and shades or colors, the whole being arranged in a manner too clearly shown by the drawing to need description.

Irrespective of the colors employed, I claim—

The design for a shawl-pattern, as represented in and by the accompanying drawing.

In testimony whereof I have signed my name to this specification in the presence of two subscribing witnesses.

FRED. WINK.
